AUTOMOBILE FENDER TRIM

Romanus La Mont, Detroit, Mich.

Application August 18, 1949, Serial No. 4,580

Term of patent 3½ years

(Cl. D14—6)

To all whom it may concern:

Be it known that I, Romanus La Mont, a citizen of the United States, residing at Detroit, in the county of Wayne and State of Michigan, have invented a new, original, and ornamental Design for Automobile Fender Trim, of which the following is a specification, reference being had to the accompanying drawing, forming part thereof.

Fig. 1 is a vertical sectional view of an automobile fender trim constructed in accordance with my new design, taken in the direction of the arrows substantially along the line I—I of Fig. 2.

Fig. 2 is a side elevation of the trim shown in Fig. 1.

Fig. 3 is a plan view of the trim shown in Fig. 2.

I claim:

The ornamental design for an automobile fender trim, as shown.
